Peter Baumgras Inventor

United States Patent Office.

PETER BAUMGRAS, OF WASHINGTON, DISTRICT OF COLUMBIA,
ASSIGNOR TO GEORGE W. THOMSON.

Design No. 3,229, dated November 10, 1868.

DESIGN FOR A VAPOR-BURNER.

The Schedule referred to in these Letters Patent and making part of the same.

To all whom it may concern:

Be it known that I, PETER BAUMGRAS, of Washington, in the District of Columbia, have invented a new and useful Design for Vapor-Burners; and I do hereby declare the following to be such a description of the same as will, in combination with the accompanying drawings, which make part of this specification, enable others to construct and make the design which I claim to be my invention.

In the drawings—

Figure 1 is a full side view of my design.

Figure 2 is a section in line x x , fig. 1.

Figure 3 shows the naked burner, without the ornamental portions.

Figures 4, 5, 6, 7, and 8 are views of separate parts of my design, showing their construction.

Like letters of reference indicate like parts in the several figures.

A, fig. 3, shows the bare vapor-burner, over the part a of which slides the part B of my design. This part B consists of a six-armed star, of leaves stamped out, as is partially shown in fig. 4, having a hole, b , in the centre, which slips over part a of burner A. The leaves are bent up, to form the design B, being a lilly-shaped corolla, the top of each alternate leaf being bent into a scroll, as shown in fig. 5, and of each other alternate one, as shown in fig. 6. A section in line x x , fig. 1, is shown in fig. 2.

To the part c of the burner A, being the regulating-

screw, is affixed the part C of my design, stamped out, as partially shown in fig. 7, leaves, d , being formed on two opposite sides of the cup e , and short stumps, f , on the other two sides. The cup e has a flat bottom and corrugated outwardly-inclined sides. The serrated leaves d have, near the cup, two ears, g , and at their ends short pieces, h . The leaves are folded, as shown in fig. 8, and bent downward, the ends, h , being twisted and interlocked under the cup e , while the ears g , being bent one against the other, form upward and outwardly-extending projections, g' .

The short pieces, f , have on each side two straight ears, i , and a straight piece, j , at their ends. These pieces f are bent upwardly, as shown in fig. 1, and curved, the pieces j entering at opposite sides into the piece c of the burner, the ears i being bent upwardly and toward each other.

The whole forms a design for vapor-burners, shown complete in fig. 1.

Having thus described my invention,
What I claim as new, and desire to secure by
Letters Patent, is—

The design for a vapor-burner, herein described and shown.

PETER BAUMGRAS.
